WINDOW SHADE ADJUSTER

John L. Hyland, New York, N. Y.

Application June 1, 1936, Serial No. 82,969
Renewed April 10, 1939

8 Claims. (Cl. 156—27)

This invention relates to an improvement in window shade adjusters, more particularly for adjusting the position of a window shade bodily with respect to a window, whereby the shade may be moved bodily to different vertical and angular positions with respect to the window.

The object of the invention is to provide suitable shade effect, while at the same time maintaining proper ventilation at the top and bottom of a window without rattling of the shade. This is accomplished by the bodily adjustment of the shade vertically and angularly relative to the window which leaves ventilating space at the top and bottom, when desired, allowing free circulation of air through the top and bottom of the window into and out of the room for complete and thorough ventilation thereof, without creating an undue disturbance due to the shaking and rattling of a shade as was frequently the case heretofore. By providing proper ventilation for the room, by letting fresh air in at the bottom of the window and foul air and gases out at the top, proper ventilation is obtained which will materially improve living conditions for a large number of people. Furthermore, this ventilator and noiseless shade will allow users thereof to sleep peacefully although they may have been awakened heretofore almost every night by noisy window shade equipment.

By adjusting the shade to different bodily positions relative to the window, it is useful for various other purposes, such as an awning, a ventilator, a light reflector, etc.

Another feature of the present invention is its use to prevent the shade from rolling up at the top and getting out of reach, as frequently occurs with shades of the type used heretofore, and it also serves to hold the shade against blowing through the open window out of its proper normal position.

In carrying out these objects of the invention, the shade is supported by balance weights which are enclosed in channels fastened to opposite sides of the window frame. In addition to the balance weights, a pair of arms is provided to position the shade bodily with respect to the window and to adjust it to different positions, which arms are connected with a support for the shade and have provision for detachable and adjustable connection with the channels.

A preferred embodiment of the present invention is illustrated in the accompanying drawings, in which:

Fig. 1 is a front elevation of the shade adjuster applied to a window;

Fig. 2 is a vertical sectional view therethrough;

Fig. 3 is a top plan view of a window showing the shade in a different position with respect thereto;

Fig. 4 is an enlarged plan view of the shade holder and arm adjuster;

Fig. 5 is a front elevation thereof;

Fig. 6 is an enlarged view of the guide and weight supporting the carrier.

In the preferred embodiment of the invention illustrated in the accompanying drawings, the window frame is designated W, and has secured to the inner side thereof a pair of channels 1, which extend vertically along the inner side 10 thereof, and each of these channels is sectional with the sections telescoped so as to fit windows of different sizes.

The shade is designated generally by the numeral 2, and may be of the spring-type having 15 pintles 3 at the opposite ends thereof, which are received in brackets 4 of a shade carrier 5, which is also made in two sections telescopically connected together and which extends transversely of the window. The carrier 5 has cords 6, secured to opposite ends thereof for supporting the same, and the shade carried thereby, which cords 6 extend over guides 7 at the top of the channels 1, thence downwardly into the channels, and having counter-weights 8, attached to the 20 lower ends thereof, or the cords may extend through openings in the counter-weights and then upwardly for attachment to the channels or frame at the opposite side, allowing the counter-weights to work in loops of the cords, in 25 order to have less movement of the counter-weights vertically in the channels.

The carrier 5 has sockets 9 formed therein, and receiving the inturned ends 10 of arms 11 which are used to adjust the shade to different positions 35 with respect to the window. The arms 11 are formed of spring metal normally tending to spread apart, in order to bear against the inner sides of the window frame. Each arm 11 has its opposite end formed in a reversed bend 12, which 40 serves as a hand-hold for adjusting the arms and shade, and this portion 12 also serves to hold the window curtains and drapes in place when the window is open. The extreme end 13 of the arm is formed to enter any one of a series of 45 holes 14, formed in the inner side of the channel 1, in order to hold the arm in a desired position.

By grasping the portions 12 of the arms, the shade may be moved bodily up or down, as desired, with respect to the window, which upward 50 movement is assisted by the counter-weights 8 on the cords 6, and in Fig. 1 the shade is shown in the position where it allows the window to be open at top and bottom for complete ventilation of the room. When the shade is moved up or 55 down to the desired position, the ends 13 of the arms 11 are inserted into holes 14 in the channels, in order to hold the shade in this position.

In Fig. 1, the shade is flat against the window in which position it serves merely as a shade, but 60

it should be evident from Figs. 2 and 3, that it may be adjusted to other positions to serve as an awning, a light reflector, draft protector, or it may be moved to one side or other of the window, so as to allow light to come into the room by one side of the window from which the shade is moved, while the shade covers the other side only, as shown in Fig. 3, and may serve to reflect light to the opposite side. In that position, only one arm 11 need be attached to its adjacent channel, while the other arm may hang free and the shade will then stand out at an angle to the window for the purpose described.

As shown more particularly in Fig. 2, the shade extends laterally from the window with its upper edge spaced therefrom, so as to serve as an awning, or the like, or if lowered to the bottom of the window, it will serve as a draft protector, but in either event the shade is held forwardly away from the window by the arms 11, which are attached to the carrier 5 and which serve to swing the shade forwardly from the window on the cords 6.

In the different adjusted positions of the shade, particularly as represented in Fig. 2, the free edge of the shade opposite the roller 2, should be fastened to the channels 4, in order to hold the shade in place and to prevent rattling or blowing thereof by the wind. This is accomplished in this form of the invention by the provision of pins or rods 15, which are shaped to enter the holes 14, if desired, or to press against the inner sides of the channels in order to hold the free edge of the shade in place by friction. The pins or rods 15 are spring-pressed in order to hold them in an extended position normally.

By the provision of inside awnings for the room, rather than outside awnings, a very large percentages of fires will be prevented which have resulted heretofore from dropping lighted cigarettes or matches on the awnings. At the same time accidents resulting from putting up or taking down or adjusting awnings will be eliminated. The adjustment of the shade to prevent a view into the room from the outside, may be made without disturbing the ventilation and lighting of the room, so as to let in light and air from the outside and yet excluding vision into the room.

50 I claim:

1. In a window shade adjuster, the combination of a window frame, a pair of upright supports having vertically spaced openings therein, a window shade carrier, arms each having one end engaging the carrier and the other end in position to enter an opening in the adjacent upright support to hold the carrier in a predetermined lateral position, relative to the window frame, and means other than said arms for supporting the weight of the carrier for freedom of movement of the carrier bodily laterally relative to the window frame.

2. In a window shade adjuster, the combination of a window shade carrier, flexible means for supporting opposite ends of the carrier for bodily lateral movement of the window shade and carrier relative to a window, upright guides on opposite sides of the window and having a plurality of vertically spaced openings therein, and spring arms on opposite sides of the carrier and each having an end engaging the carrier and the opposite end in position to engage in an opening of the adjacent guide.

3. In a window shade adjuster, the combination with a window having vertically arranged

channels at opposite sides thereof, a window shade carrier, cords supporting opposite ends of the carrier free of the window for lateral movement relative thereto, counter-weights within the channels and attached to the cords normally tending to move the carrier to an elevated position, said channels having vertically spaced openings in the inner sides thereof, and spring-arms each having an end in position to engage the carrier and the opposite end in position to engage in an opening of the adjacent channel.

4. In a window shade adjuster, the combination with upright guides, of a window shade carrier, flexible means connected with opposite ends of said carrier and supporting the same for bodily movement up and down relative to the guides and for forward movement relative thereto, at least one of said guides having vertically spaced stops, and an arm connected with said carrier and detachably engaging one of said stops for positioning the carrier laterally relative to the adjacent guide.

5. In a window shade adjuster, the combination with upright guides, of a window shade carrier supporting a window shade, flexible means connected with opposite ends of said carrier and supporting the same for bodily movement up and down and forwardly relative to the guides, said guides having vertically spaced openings therein, arms each having one end connected with an end of the carrier and the opposite end detachably engaging one of the openings in the adjacent guide for positioning the carrier laterally relative to the guides, and means for attacking the free end of the window shade to the guides. 35

6. In a window shade adjuster, the combination with upright guides, of a window shade carrier, flexible means connected with opposite ends of said carrier and supporting the same for bodily movement up and down and forwardly relative to the guides, said guides having vertically spaced openings therein, and spring arms each having one end detachably and pivotally connected with an end of the carrier and the opposite end detachably engaging one of the openings in the adjacent guide for positioning the carrier laterally relative thereto.

7. In a window shade adjuster, the combination with upright hollow guides, of a window shade carrier, a cord connected with each end of said carrier and extending into the adjacent hollow guide and supporting said end therefrom, a weight attached to each cord in the guide for raising said carrier bodily relative to the guides, said carrier being free for bodily movement transversely relative to the guides while supported on the cords, said guides having vertically spaced openings therein, and arms pivotally connected with opposite ends of the carrier and having free ends in position to engage the openings in the guides for positioning the carrier laterally relative thereto.

8. In a window shade adjuster, the combination with upright guides having vertically spaced openings therein, of a window shade carrier having a window shade, means for supporting said carrier for movement laterally relative to the guides, and pins attached to the edges of the free end portion of the shade in position to engage in the openings to hold said free end portion in proper position between the guides and the shade inclined in awning-effect when said carrier is positioned laterally relative to the guides. 70
